UNITED STATES PATENT OFFICE.

FRANCES HIGBIE, OF BROOKLYN, NEW YORK.

MUSIC-STAND.

SPECIFICATION forming part of Letters Patent No. 514,751, dated February 13, 1894.

Application filed September 20, 1893. Serial No. 485,950. (No model.)

To all whom it may concern:

Be it known that I, FRANCES HIGBIE, of Brooklyn, in the county of Kings and State of New York, have invented a new and useful 5 Improvement in Music-Stands and other Articles, of which the following is a full, clear, and exact description.

My invention relates to an improvement in clamp joints, and it has for its object to provide a means whereby any horizontal object, such as a music rest, bracket or table for example, may be adjustably held upon an upright support without the assistance of set screws or equivalent devices.

15 A further object of the invention is to so construct the connecting medium between the horizontal and vertical objects, that the former may be expeditiously and conveniently adjusted to any point in the length of 20 the latter, and the moment the point to which the adjustment is to be made is reached, by releasing the horizontal music rest, bracket or other object, it will remain stationary upon the support, and the more weight that is 25 placed upon the horizontally located object the more closely will the said object be bound to its support.

The invention consists in the novel construction and combination of the several 30 parts, as will be hereinafter more fully set forth and pointed out in the claim.

Reference is to be had to the accompanying drawings forming a part of this specification, in which similar figures and letters of reference indicate corresponding parts in all the 35 views.

Figure 1 is a front elevation of a music stand in which the features of the invention are incorporated. Fig. 2 is a broken vertical 40 section of the same; and Fig. 3 is a sectional view taken through line $x-x$ in Fig. 2.

In carrying out the invention I have illustrated a support A, which is in the form of a bar, and which may be of any cross sectional 45 shape. The support A, may be properly termed a standard, and the object shown as supported by the standard is a music rest B; but it will be understood that any bracket or equivalent of the music rest may be connected 50 with the standard.

The music rest B in the drawings is shown

as rectangular, but the essential feature of the invention lies in the connecting medium which is to unite the rest, bracket or other article with the standard A. In the present 55 instance the connecting medium consists in a neck or lug 10, which neck or lug is given an upward inclination from the rest, and the neck or lug is provided with an opening 11, extending through it from top to bottom. The 60 opening is wider at the top than at the bottom, and the opposite side walls of the opening are inclined in opposite directions, as, for example, what may be termed the inner side wall a , is inclined from the bottom upward 65 and outward in direction of the body, while the opposite side wall a' , is inclined from the bottom upward and outward away from the body, as is best shown in Fig. 2. Thus the two lower opposite points in the bottom portion of the opening 11, would represent the upper and leverage point designated as 12, and the lower and fulcrum point designated as 13, and these two points of contact are in different horizontal planes, and are adapted 70 to impinge upon opposite sides of the standard or support.

One of the important features of the invention consists in so constructing the clamp that it will not, when adjusted, wabble or tip sideways, but will remain perfectly steady. This is accomplished by causing the point of leverage to diametrically meet the point of fulcrum, thus providing for a bearing of the article to be supported, all around the support. 80

It will be readily observed that by tilting the rest B upwardly, the fulcrum point 13 will be carried out of engagement with the standard or support A, as likewise the leverage point 12, and the rest may be carried up and 90 down the standard or support to whatever point fancy may dictate or occasion may require. The moment, however, that the rest is released and drops to its normal or horizontal position, the leverage point 12, will engage 95 with one side of the support or standard, and the fulcrum point 13 with an opposite side of the support or standard, and as the two points are in different horizontal planes one will serve to counteract the other, as they impinge 100 one below the other at practically different angles upon the support or standard, and

therefore, the greater the weight placed upon the rest the firmer the rest will be clamped to its standard or support.

As has heretofore been stated the word music rest is simply used to designate one article that may be held adjusted upon a vertical support, but any article adapted to be held in a horizontal or approximately horizontal position may be as well supported as a music rest.

Having thus described my invention, what I claim as new, and desire to secure by Letters Patent, is—

A support and an article to be supported, the latter being provided with an opening wider at one end than at the other, said opening having its wall inclined, one portion of the wall serving as a point of leverage and the

opposite point as a fulcrum point, the two points being in two different horizontal planes located at the same end of the opening and adapted to impinge on opposite sides of the support, both the fulcrum and leverage portions of the wall of the opening engaging with about one-half of the circumference of the support, forming a substantially circular bearing in a horizontal direction, and whereby the article to be supported may be adjusted upon the support and held at any desired point in the length of the support without danger of rocking, substantially as shown and described.

FRANCES HIGBIE.
